UNITED STATES PATENT OFFICE

2,009,080

METHOD OF RADIO COMMUNICATION

Henri Chireix, Paris, France, assignor to Compagnie Generale De Telegraphic Sans Fil, a corporation of France

Application December 27, 1933, Serial No. 704,093
In France December 27, 1932

6 Claims. (Cl. 250—17)

The present invention relates to signalling systems employing high frequency currents for the transmission and constitutes in particular an improvement or modification in the transmitter of modulated waves described in the United States patent specifications Nos. 1,882,119 and 1,892,383.

The invention will be more readily understood with reference to the accompanying drawings in which:

10 Figure 1 shows a general arrangement of the transmitter according to the invention;

Figure 2 shows a potential diagram in the output and input circuits of the last amplification stage of the transmitter;

15 Figure 3 indicates a curve showing the angle between input vectors of Fig. 2 in function of the angle between output vectors of the same figure;

Figures 4, 5 and 6 show three species of arrangement contained within the rectangle 15 of Fig. 1.

The Figure 1, analogous to the Fig. 2 of the United States Patent 1,882,119, shows a transmitter comprising two differential circuits 2 and 2', each one of which is traversed by a current of practically fixed amplitude, but of modulated phase, the two phase modulations being made in opposite senses. These phase modulated currents are obtained from a carrier wave generator 8 coupled with the circuits 2, 2' through the couplings 9, 9'. The circuits between the generator 8 and the coupling inductances 9 and 9' are such that the carrier waves fed from 8 to 9 and 9' are in phase opposition. The couplings 9 and 9' deliver unmodulated components of phase modulated currents to the amplifiers 14 and 14'. The generator 8 is coupled, moreover, through the coupling 10 with a modulating arrangement 11 to deliver thereto carrier waves in phase quadrature with respect to the waves in 9 and 9'. The

40 modulator 11 is controlled by a microphone 12 or other suitable modulation means and coupled with the circuits 2, 2' through the couplings 13, 13' in such a manner that there are delivered two amplitude modulated components which are opposed to one another and are, moreover, in quadrature to the said unmodulated components flowing through the circuits 2, 2'. The superimposition of one unmodulated and one modulated component in each circuit gives the resulting fixed amplitude but phase modulated current, the two phase modulations being made in opposite senses. Each of these currents is amplified in the amplifiers 14, 14' and both currents are combined in a

45 circuit contained within the rectangle 15 to sup-

plying the antenna 5 with a high frequency amplitude modulated wave.

It has been further shown in my Patent #1,946,303, resulting from application Ser. No. 623,333, filed the 19th July, 1932, that it is necessary in order to obtain the maximum efficiency from the output of the last amplification stage, to detune the oscillating circuits of anode the one to higher values and the other one to lower values in such manner as to compensate for a given condition of the reactive energy due to the load reaction. This necessary detuning causes as such a disadvantage which the present invention aims to overcome. Under conditions where the compensation is a correct one, the excitation of the grid is exactly in phase with the voltage developed in the plate circuit, but under all other conditions this is no longer true with the result that the amplifier tubes operate with an impedance different from a pure resistance. It will therefore be found that if during the cycle of modulation the phase of voltage U_1 and U_2 at the terminals of the output circuits varies by the value α (across sectioned zone in Figure 2) the phase of the excitations V varies by the quantity β , whereby β is greater than α .

Furthermore Figure 3 shows the course of the curve indicating the relation between the angle of the phase difference ϕ_p between the vectors U in the plate circuit and the angle of the phase difference ϕ_g between the vectors V in the grid circuit. This curve intersects the 45° line at the angle effecting the compensation. This disadvantage therefore involves a lack of linearity in the modulation in that the antenna current does not vary quickly enough in the region where the compensation of the reactive power is carried out.

According to the present invention this deficiency can be remedied in that the inverse defect for the grid circuit is produced in the opposite sense, that is to say in effecting the condition in which the angle through which the excitation of the grid of the final stage passes be greater than the angle through which the electromotive force of the excitation of this circuit, or the excitation of the preceding amplification stage passes. With a sweeping α sufficient so as to obtain the sweeping zone β of the grid excitations the aforementioned deficiency will be completely compensated.

The solution for accomplishing this result and which forms the object of the present invention consists of applying the invention of U. S. Patent #1,946,303 both to the grid circuit and to the plate circuit of the amplifier end stage (or to a

circuit preceding the end stage), and under conditions in which the load of the grid circuit is at maximum when the useful load in the output end circuit is at minimum and vice versa. It will also be seen that whatever circuit may be adapted for obtaining modulation by the difference in phase, the result will be reached in such a way that the reactive power causing the load in the grid circuits and in the plate circuits of the same tube, is of inverse sign (effect of self inductance by the one, effect of the capacitance by the other one). Consequently in order to obtain a true tuning of the grid and plate circuits for a given condition it is required to detune the grid and plate circuits of the same tube or of the same amplifier branch in different senses.

An embodiment of the invention is shown in Figure 4 by way of example which represents an arrangement contained in the rectangle 15 of Fig. 1, in which 1 and 1' designate two grid circuits receiving from couplings 2, 2' the excitations different in phase and preferably in opposite phase at small loads while the point opposite the grids of these circuits is connected to the usual negative pole. These oscillatory circuits excite tubes 3, 3' which supply respectively the oscillatory circuits 4, 4'; 5 represents diagrammatically the load resistance, for instance a tuned antenna, and 6 are the lead capacities and coil inductances as ordinarily used.

The oscillating output circuits 4 and 4' are chosen in accordance with Patent #1,946,308 so that 4 is tuned below the carrier wave and 4', for instance, above the latter. According to the improvements obtainable by the present invention, the circuits 1 and 1' are also detuned but in opposite senses that is to say when 4 is detuned below the carrier wave in the case of the example shown, 1 is detuned above it and when 4' is detuned above the carrier wave, 1' must be detuned below it. Finally these circuits 1 and 1' operate upon a common load represented by the resistances 7.

It will also be realized that the small loads in 5 on the contrary correspond with the great loads in 7 and vice versa.

It will be seen, in effect, that the load resistance 5 is affected by the geometrical sum of the vectors U, whilst the resistance 7 is traversed by a current due to the geometrical difference of the vectors V.

These conditions have been indicated by means of conventional signs + and - as indicated in the figure.

There are numerous variations of the same characteristic possible as for instance those shown in Figures 5 and 6 in which equivalent elements are designated by the same reference numerals as in Figure 4.

In Fig. 5, the resistance 1 is loaded by the geometrical sum of vectors V, whilst the resistance 5 is charged by the geometrical difference of vectors U. In Fig. 6, the resistance 5 is as in Fig. 4 charged by the geometrical sum of vectors U, but the circuits 1 and 1' are so interconnected that the resistance 7 is affected by the geometrical sum of vectors (+V) and (-V). In all the cases of the figures it will be readily seen that with the small loads of the plate circuits correspond the heavy loads of the grid circuits.

The detuning of the grid and plate circuits of the same tube on the other hand are carried out at opposite senses. For all cases the excitations of small loads is marked by the conventional signs + and -.

The application of the present invention does not involve supplementary losses since in fact the resistances 7 in Figure 4 must always be present so as to assure stability and sufficient damping effect of the grid circuits. If the invention is not applied it is simply necessary to ground the center of the resistances and to tune the circuits 1 and 1'. The modification introduced by the invention simply consists of avoiding of this grounding and of a different tuning.

Having thus described my invention and the operation thereof, what I claim is:

1. An amplitude modulated wave transmitter comprising a source of electrical energy of carrier frequency, two differential circuits coupled with said source and containing each an amplification chain, oscillating circuits disposed in the output and in the input of the last amplifier stage in each chain, the two output oscillating circuits being detuned respectively the one above, the other below the said carrier frequency, whilst the corresponding input oscillating circuits are inversely tuned, the one below, the other above the carrier frequency, means coupled with the said source for diverting a portion of energy and for transforming its phase in quadratic relationship to the original phase, means for amplitude modulating the last said energy portion, means for superimposing the modulated energy on the unmodulated energy in each of the differential circuits so that the resulting wave in each circuit is phase modulated and is of practically fixed amplitude and so that the phase modulations vary in opposed senses in the respective circuits, and a common output circuit coupled to said output oscillating circuits for combining the phase modulated waves to produce an amplitude modulated wave.

2. An amplitude modulated wave transmitter comprising a source of electrical energy of carrier frequency, two differential circuits coupled with said source and containing each an amplification chain, oscillating circuits disposed in the output and in the input of the last amplifier stage in each chain, the two output oscillating circuits being detuned respectively the one above, the other below the said carrier frequency, whilst the corresponding input oscillating circuits are inversely, detuned, the one below, the other above the carrier frequency, means for modulating the phase of the energy in the said differential circuits so that the resulting wave in each circuit is phase modulated and is of practically fixed amplitude and so that the phase modulations vary in opposed senses in the respective circuits, and a common output circuit coupled to said output oscillating circuits for combining the phase modulated waves to produce an amplitude modulated wave.

3. A transmitter as recited in claim 2 in combination with means for rendering the common output circuit load maximum when the load of the input oscillating circuits is minimum and vice versa.

4. A transmitter as recited in claim 2 comprising at least one resistance interconnecting the input oscillating circuits of the last amplifier stages of the two differential circuits.

5. A transmitter as recited in claim 2 comprising at least one resistance interconnecting the input oscillating circuits of the last amplifier stages of the two differential circuits, means for applying to the said resistance the difference of the potentials in the said input circuits, and means for applying to the output common circuits

the sum of the potentials in the output oscillating circuits of each of the differential circuits.

6. A transmitter as recited in claim 2 comprising at least one resistance interconnecting the 5 input oscillating circuits of the last amplifier stages of the two differential circuits, means for applying to the said resistance the sum of the

potentials in the said input circuits, and means for applying to the output common circuit the difference of the potentials in the output oscillating circuits of each of the differential circuits.

5

HENRI CHIREIX.
